UNITED STATES PATENT OFFICE.

UMBERTO FOPPIANO, OF VALPARAISO, CHILE.

PAINTBRUSH GUARD.

Application filed November 17, 1924. Serial No. 750,485.

To all whom it may concern:

Be it known that I, UMBERTO FOPPIANO, a subject of the King of Italy, residing at Valparaiso, Chile, have invented new and useful Improvements in Paintbrush Guards, of which the following is a specification.

This invention relates to attachments to or accessories for use in connection with paint brushes, the guard operating to catch and retain any paint or other liquid running down the brush as for instance when painting ceilings and the like.

An important object is the provision of a guard of this character which is formed from a single piece of resilient sheet metal pressed or otherwise formed into the necessary shape and provided with means for attachment to an ordinary brush without the employment of auxiliary securing elements of any kind whatsoever.

An additional object is the provision of a device of this character which on account of retaining the paint running back down the brush may be tipped downwardly at any time in order that the accumulation of paint may flow onto the brush and replenish the supply thereon.

An additional object is the provision of a device of this character which will be simple and inexpensive in manufacture, easy to apply, positive in action, efficient and durable in service, and a general improvement in the art.

With the above and other objects and advantages in view, the invention consists in the details of construction to be hereinafter more fully described and claimed and illustrated in the accompanying drawings, in which:

40 Figure 1 is a perspective view of a paint brush equipped with my device.

Figure 2 is a longitudinal section through the brush and the attachment.

45 Referring more particularly to the drawings, the letter A designates, broadly, a paint brush of any ordinary or preferred construction here represented as including a handle B upon which is secured the brush head or bristles C held in place by a ferrule D which in the present instance is represented as consisting of wire coiled about the butt end of the brush and securing the bristles to the handle. However, there is no limitation regarding the particular type 50 of brush as the device is adapted to be engaged upon any ordinary brush.

In carrying out the invention I provide a guard or shield formed as a cylindrical shell 10 of greater diameter than the ferrule of the brush to which it is to be applied. While this shell is described as cylindrical, it should be understood that this is the shape provided only in case the attachment is designed for use in connection with round brushes as it is obvious that the guard or shield would have to be of some other shape if the brush were rectangular or flat. In other words, the shell must necessarily conform to the shape of the brush itself. One end of the shell is outwardly flared as indicated at 11 while the other end is somewhat constricted as shown at 12 and formed with an upstanding flange 13 which has its sharpened edge 14 so as to be capable of penetrating engagement between the mass of 75 bristles at the butt end of the brush.

The attachment is applied by slipping it over the handle B with the flared end 11 disposed toward the brush head, the device being moved along the handle until it is arranged in surrounding relation to the ferrule D, with the sharpened edge 14 of the flange 13 engaging against the butt end of the brush head. Pressure is then applied to the device by any desired means 80 in order to force this flange into penetrating engagement within the mass of bristles and it is obvious that the device will then be held firmly in place.

85 In the use, it is apparent that when painting ceilings or other places over the head of the operator there is a natural tendency of the paint or other liquid used to flow down the brush and onto the handle. However, with the attachment applied it is evident that this liquid, or the like will accumulate within the guard or shell so that it cannot flow down onto the brush with the result and disadvantages of making the handle slippery and soiling the hands of the operator. Whenever any appreciable quantity of paint or other liquid has accumulated within the guard it may be tilted downwardly in an obvious manner so as to permit the paint or other liquid to flow back 105 onto the brush head to replenish the supply thereon.

110 From the foregoing description and a study of the drawings it will be readily apparent that I have thus provided a simply constructed and extremely inexpensive device for the purpose specified which

will efficiently perform all the functions for which it is intended and which on account of its simplicity possesses no features likely to get out of order.

8. While I have shown and described the preferred embodiment of the invention, it should be understood that I reserve the right to make such changes in the form, construction and arrangement of parts as 10 will not depart from the spirit of the invention or the scope of the subjoined claims.

Having thus described the invention, I claim:

1. In combination with a paint brush, a 15 guard device formed as a shell of greater diameter than the brush ferrule, one end of the shell being formed with a reversely

extending flange embedded within the butt end of the brush head.

2. A paint brush guard comprising a 20 shell or substantially the same configuration as the ferrule of a paint brush, said shell having one end flaring outwardly and its other end somewhat constricted and formed with a reversely extended flange having 25 a sharpened edge, the shell being disposed in encircling relation to the ferrule of a paint brush with said flange engaged within the butt end of the mass of bristles constituting the brush head.

30 In testimony whereof I affix my signature.

UMBERTO FOPPIANO.
